UNITED STATES PATENT OFFICE.

WESTON L. BROWN, OF LAKewood, OHIO.

TOILET-PAPER PACKET.

1,286,929.

Specification of Letters Patent. Patented Dec. 10, 1918.

Application filed May 29, 1918. Serial No. 237,278.

To all whom it may concern:

Be it known that I, WESTON L. BROWN, a citizen of the United States, resident of Lakewood, county of Cuyahoga, and State 5 of Ohio, have invented new and useful Improvements in Toilet-Paper Packets, of which the following is a specification, the principle of the invention being herein explained and the best mode in which I have 10 contemplated applying that principle, so as to distinguish it from other inventions.

My invention relates to a paper packet and particularly to such an article so constructed as to provide a convenient and economical 15 pocket packet of independently removable sheets of toilet paper.

The annexed drawings and the following description set forth in detail certain means embodying my invention, the disclosed 20 means, however, constituting but one of various mechanical forms in which the principle of the invention may be applied.

In said annexed drawings:

Figure 1 represents a front perspective of 25 my improved packet provided with a cardboard or other cheap cover member adapted to be discarded in its entirety when the sheets of paper are entirely used, or adapted, if a leather, canvas or other permanent cover is 30 utilized, to be discarded in part and to permit the ready and satisfactory insertion and retaining of the packet in said permanent cover by the part of the temporary cover which is not discarded; Fig. 2 represents a 35 rear perspective of the parts shown in Fig. 1; Fig. 3 represents a side elevation of the parts shown in Fig. 1; Fig. 4 represents a perspective of the closed position of the parts shown in Fig. 1; Fig. 5 represents a side elevation 40 of the parts shown in Fig. 1 after a part of the temporary cover has been discarded so as to permit the insertion of the packet in the permanent cover; Fig. 6 represents a front perspective of the parts shown 45 in Fig. 5 after they have been inserted in a permanent cover; Fig. 7 represents a vertical cross-section of the parts shown in Fig. 6 in a somewhat more closed position; and Fig. 8 represents a perspective of the closed 50 position of a permanent cover containing the filler packet.

Referring particularly to Figs. 1 to 5, I have indicated therein a plurality of independent sheets 1 of toilet paper secured to a 55 cardboard or other cheap cover 2 by means of a suitable fastener 3. Said sheets 1 of

paper are adapted to be folded upon themselves twice to form a filler packet incased within the cover 2. The latter consists of a body portion 2' and a tab portion 2". Said 60 body portion is adapted to be bent upon itself for incasing the filler packet and a slit 4 is formed in said body portion in which the tab 2" is adapted to be inserted to hold the packet closed. 65

I have also provided in the body portion 2' a plurality of perforations 5 disposed transversely of said body portion, somewhat removed from the folding edge 2", and across the entire body. These perforations 5 are 70 disposed at a distance from the common edge 2' of the body portion 2' and the tab 2" approximately equal to the depth of the tab 2". Thus when that part of the body portion 2' below said perforations 5 is detached, the 75 tab 2" can be bent back upon the remaining part of the body portion to form a reinforced holding member adapted to be slipped into the pocket or strap of a permanent cover. The disposition of the perforations 5 80 along a line somewhat removed from the edge 2" obviates any weakening or breaking of the cover due to the repeated opening of the packet. A permanent cover is illustrated in Figs. 6, 7, and 8 and comprises a 85 main portion 6 formed with a flap 7, said main portion and flap being provided, respectively, with any desired cooperating fastening means such as a stud 8 and eyelet 9. The pocket or strap of this permanent cover 90 within which the reinforced holding member of the temporary cover is adapted to be inserted, is represented by the ordinal 10, Fig. 7.

I desire to particularly point out that the 95 above-described construction adequately protects the filler sheets, even with the temporary cover furnished with such sheets; also, that the construction is one which permits the independent removal of the sheets 100 as a whole without leaving any remaining ragged or torn edges of the paper in the backing or cover member.

What I claim is:

1. A toilet paper packet comprising a 105 backing member provided with a main portion and a tab portion, said main portion being adapted to be doubled back upon itself to form a cover and being perforated so as to enable the detachment of a definite part 110 thereof, said main portion and said tab portion being formed to hold the backing mem-

ber normally closed; a plurality of independent sheets of toilet paper folded within the space between the opposing faces of said cover; and means attaching said sheets to said backing member.

2. A toilet paper packet comprising a backing member provided with a main portion and a tab portion, said main portion being adapted to be doubled back upon itself to form a cover and being perforated so as to enable the detachment of a definite part thereof, said main portion also being provided with a slit adapted to receive said tab; a plurality of sheets of toilet paper folded within the space between the opposing faces of said cover; and means attaching said sheets to said backing member.

3. A toilet paper packet comprising a backing member provided with a main portion and a tab portion, said main portion being adapted to be doubled back upon itself to form a cover and being transversely perforated along a line somewhat removed from the doubled back edge so as to enable the detachment of a definite part of said main portion, the latter also being provided with a slit adapted to receive said tab; a plurality of independent sheets of toilet paper folded within the space between the opposing faces of said cover; and means attaching said sheets to said backing member.

Signed by me, this 20th day of May, 1918.

WESTON L. BROWN.
